UNITED STATES PATENT OFFICE.

GUSTAV BARTHEL, OF DRESDEN, GERMANY.

VAPOR-STOVE.

992,328.

Specification of Letters Patent. Patented May 16, 1911.

Application filed September 9, 1908. Serial No. 452,201.

To all whom it may concern:

Be it known that I, GUSTAV BARTHEL, a subject of the German Emperor, residing at Dresden, Germany, have invented certain new and useful Improvements in Vapor-Stoves, of which the following is a specification.

The present invention has reference to improvements in spirit stoves and relates 10 more especially to improvements in that type of stoves or burners in which the liquid fuel is vaporized by an auxiliary flame, and the vapor is then mixed with air and then burned, part of this mixture being used for 15 feeding the auxiliary flame for sustaining vaporization; and the object of the invention is to obtain a more perfect vaporization of the fuel and allow of the burner being quickly and easily taken apart for cleaning 20 purposes, and lastly to so dispose the vaporizer that it in no way interferes with the main flame.

In order to make my invention more readily understood, I will now describe it with 25 reference to the accompanying drawing, in which—

Figure 1 represents a vertical section through a preferred form of my new stove, partly in section; Fig. 2 is a cross-section on 30 line *a—a* of Fig. 1, and Fig. 3 is a perspective view of the burner part proper.

The vaporizer consists of the straight tube —1— filled with porous material —2—, such as wires, asbestos threads or the like. At 35 one end this tube is closed by a nut —3—, and at the other end there is provided a screw spindle —4— with head —5—, serving as needle valve, and coöperating with the passage —6— in the wall —7— dividing 40 the vaporizing tube —1— from the depending short tube —8—. The tube —1— extends through the mixing chamber —10— which communicates above with the burner head —11— and laterally with the mixing 45 tube —12—. The burner head is provided with passages —13— through which the useful flame is fed with gas, and with passages —14— for the auxiliary flame used for heating the vaporizing tube —1—. For aiding 50 this auxiliary flame there are provided in the wall of the mixing chamber —10— further vapor passages —15—.

From the reservoir —16— the fuel is conducted into the vaporizer through the

pipe —17—. For starting the stove, a suitable fuel in the pan 18 is ignited to heat the tube —1— to vaporize the fuel therein. The burner part proper is surrounded by brackets —19— carrying a support ring —20— of the well known type. The fuel vapor generated in the preheated vaporizer passes through the passage —6—, the valved spindle —4— regulating the amount, issues out of the opening —9— in the short tube —8— and over into the mixing tube —12—, entraining thereby atmospheric air and intimately mixing therewith within the mixing tube and chamber. From here the mixture enters the burner head —11— and issues through the passages —13— and —14—. Mixture also 70 issues from the orifices 15.

Owing to the rapid and very thorough vaporization, the porous fuel carrier —2— soon clogs up with impurities and it must be cleaned or exchanged. That is easily done 75 by unscrewing the nut —3—, when the carrier can be removed. Since the vaporizer lies underneath the burner head, it does not in any way interfere with the main flame.

What I claim is:—

In a vapor stove, the combination with a burner head having top, side and bottom passages, of a mixing chamber vertically depending from and communicating with said burner head and having lateral passages, a 80 horizontal tube communicating with its inner end with said chamber and open at the other end, a vaporizer passing clear through said mixing chamber above said horizontal tube, below said burner head, and between 85 said bottom and lateral passages, a tube communicating with and depending from said vaporizer and having a lateral aperture opposite the open end of said horizontal tube, means for supplying fuel to said vaporizer, 90 fuel conducting means within said vaporizer, means for controlling the passage of fuel from the vaporizer into the said depending tube, and means for preheating said vaporizer and adjacent parts, all substantially as 95 set forth.

In testimony whereof, I affix my signature in the presence of two witnesses.

GUSTAV BARTHEL.
